UNITED STATES PATENT OFFICE.

THOMAS SLAIGHT, OF NEWARK, NEW JERSEY.

LOCK FOR RAILWAY-CARS.

Specification of Letters Patent No. 31,332, dated February 5, 1861.

To all whom it may concern:

Be it known that I, THOMAS SLAIGHT, of Newark, in the county of Essex and State of New Jersey, have invented a new and Improved Lock, Designed More Especially for Railroad Freight-Cars; and I do hereby declare that the following is a full, clear, and exact description of the same, reference being had to the annexed drawings, making 10 a part of this specification, in which—

Figure 1 is an external view of my invention applied to a car. Fig. 2 an internal view of the lock, the front plate of the case being removed as indicated by the line x , x 15 Fig. 3. Fig. 3 a section of same taken in the line x' , x' Fig. 2. Fig. 4, a detached perspective view of a slide plate pertaining to the same.

Similar letters of reference indicate corresponding parts in the several figures.

This invention consists in the employment or use of a dog and sliding plate, provided with suitable tumblers, the above parts being placed in a suitable case and used in connection with a bolt; all being arranged substantially as hereinafter shown and described, whereby a very simple and efficient self locking or spring lock is obtained.

To enable those skilled in the art to fully understand and construct my invention I will proceed to describe it.

A represents a metal plate on which the case B of the lock is placed or secured. The plate and case may be of cast metal and cast in one piece. On the plate A below the case B there are two guides a , a in which a bolt C is fitted and allowed to slide freely, the upper end of the bolt C passing into the case B and being secured therein when the 40 lock is locked.

Within the case B there is placed a slide plate D which is fitted on and between proper stumps or guides b and has a spring E acting upon it, said spring having a tendency to keep the plate D thrust forward in the direction indicated by the arrow in Fig. 4.

The slide plate D has an arm c projecting from it at right angles. This arm extends 50 down and is in contact with a dog F which works or turns on a pin d .

The dog may be described as being formed of two arms e , e' at right angles to each

other the pin d , passing through the angle or through the arms at their junction. The 55 arm c of the slide plate D, bears against a lip f of the dog F at the outer side of its angle as shown clearly in Fig. 4. The end of the arm e' of the dog F is of hook form as shown at g , and a recess h is made in the 60 bolt C to receive the hook g . Against the lip f of the dog F a spring G bears, said spring having a tendency to throw the dog F in the position shown by the red outline in Fig. 2.

H represents a series of tumblers which are fitted on a pin h and are notched at their edges as shown at i , and j , is a projection on the end of slide plate D.

When the parts are in the position as 70 shown in Fig. 2, the bolt C is locked within the case B, the dog F, retaining it, and it will be seen that in order to release the bolt C, the slide plate D must be thrown back in the direction indicated by arrow x so as to 75 allow the arms c to pass off from lip f , and permit the spring G to throw the hook g out from the recess h in the bolt as shown in red. In order to throw the plate D back in the direction of arrow x , the tumblers H require 80 to be moved by a proper key I, so that the large notches in the ends of the tumblers may be in line with the projection j , of plate D, and the latter therefore allowed to move in the direction indicated under the 85 action of the key. In showing the bolt C within the case B the end of the bolt strikes the arm e of the dog and throws the hook g of arm e' into the recess h of the bolt.

The bolt secures a hasp, shown in red, on 90 the plate A, the plate A and bolt C being attached to the car and the hasp to the door as shown in red, Fig. 1.

I do not claim the tumblers H for they have been previously used; but,

I do claim as new and desire to secure by Letters Patent—

The bolt C dog F and slide plate D the latter being provided with the arm c and all arranged to operate as and for the purpose 100 set forth.

THOS. SLAIGHT.
